UNITED STATES PATENT OFFICE

2,220,329

HAIR-WAVING PAD

Ralph D. Ham, Chicago, Ill., assignor to Products Development Corporation, Chicago, Ill., a corporation of Illinois

Application August 9, 1939, Serial No. 289,145

2 Claims. (Cl. 132—36.2)

This invention relates generally to hair-waving pads of the type used in the process of imparting so-called permanent waves to human hair by the utilization of the heat of exothermic chemical reactions.

Specifically, this invention discloses novel means for facilitating and expediting the use of the heat of exothermic reaction between a chemical solution and a metallic member for imparting a wave to hair.

The means used in the process utilizing this invention generally includes an envelope or sachet of the metallic member to be used in the chemical reaction. This may be very thin aluminum foil or the like. Contained within the sachet or envelope is a chemical or mixture of chemicals which also enters into the reaction. In the process the metallic envelope or sachet is perforated or pierced in some manner and a moistened member applied to the perforations, permitting moisture to seep therethrough into the sachet to contact said chemical or mixture of chemicals. A saturated solution of the active ingredients in the sachet or envelope is thus produced. Contact of the solution with the metal of the envelope produces exothermic heat of reaction in sufficient amounts to impart a permanent wave to a preformed tress of hair.

It is obvious that since the reaction occurs between a chemical or the like, and the metallic foil which constitutes the envelope for the chemical, the envelope will be gradually consumed and deteriorated in the process.

The chemical or the mixture which is within the envelope will, therefore, be unconfined and subject to being lost or scattered throughout the subject's hair. The general results are that the process is a messy one and may even be dangerous in consequences.

Two general methods have been used to overcome the distinct disadvantage of the above-outlined method of hair waving by use of exothermic heat or reaction. In one, the reaction is not allowed to go to its extreme, thus preserving the shell of the envelope or sachet. This is costly, since it requires thicker foil envelopes and does not permit entire use of said envelope nor does it permit all of the chemicals and the like within same to be consumed. Thus, with the shell thrown away, much of the material is uselessly destroyed.

The second method used is to enclose the entire assembly in confining apparatus or the like, so that the sachet or envelope may be held therein. This is an inefficient method, since

much heat is lost and expensive apparatus must be used. Also, handling the pad by such a method is an awkward and slow process.

It is an object of this invention to provide a hair-waving pad utilizing the exothermic heat of a chemical reaction involving a metallic member which will be so constructed as to eliminate the disadvantages caused by the deterioration of said metallic member.

The inventor's main purpose is accomplished in the present invention by the utilization of a sachet or envelope formed from a member comprising two layers of material. The inner layer is of extremely thin metallic foil and the outer layer is a sheet of chemically inert material, such as glassine paper. Said foil and chemically inert material are so intimately associated and held one to the other that the member may be handled as though it were an integral sheet of material. The layer of chemically inert material does not prevent conduction of heat through the envelope to the moistened member.

By the simple expedient generally described above, it will be appreciated that the foil may be completely consumed and the chemicals within the envelope completely utilized without in any way affecting the confining qualities of the sachet or envelope. This is possible because the inert material which backs up the foil remains intact during and after the chemical reaction in the shape of the envelope and is available for the complete confinement of all products of reaction, such as may be produced thereby, and also all ingredients remaining which did not enter into the reaction.

Other objects of the invention, therefore, are:

To provide a hair-waving pad of the character described, the envelope of which will be formed from a member comprising metallic foil backed up by a sheet of chemically inert material;

To provide a heating pad of this type which will include an envelope constructed of metallic foil backed by glassine paper;

To provide a heating pad of this type which will be effective in operation and simple in construction and assembly.

It has been found to be difficult to handle a pad of the nature described, because the surface must be perforated so that moisture may seep into the envelope or sachet from a moistened member applied to a face thereof. Time is lost in the perforating operation when same is done by the beautician prior to application of the pad to the customer's hair. Also, extra ap-

paratus is needed. There is an objection to envelopes being pre-perforated, since the material contained therein tends to sift out.

The present invention has for a collateral purpose the object of eliminating these disadvantages.

In the manufacture of the sachet or envelope, a portion of the member which becomes one face of the envelope, is provided with self-closing slits or perforations. These are formed by means impressed into the foil side of the member, so that burrs or feathers are formed on the outside of the sachet or envelope when same is formed from said member.

15 Said slits or perforations are substantially "I-shaped" and are formed so that the burrs or feathers may be pressed inwardly to a closed position. Thus, the chemicals and materials within the envelope are completely confined, 20 and at the same time sufficient moisture is permitted to seep through the slits or perforations to cause chemical reaction between a solution of the material and chemicals within the envelope and the foil or the inner surface thereof.

25 Further objects of the present invention are: To provide pre-perforated sachets or envelopes of the character described;

To provide perforations for a hair-waving pad of the character described, which will be self-closing;

To provide substantially "I-shaped" perforations for a hair-waving pad of the character described;

30 To provide in a hair-waving pad of the character described perforations having burred or feathered portions, said burred or feathered portions being on the external side of a face of said pad.

With the foregoing and other objects in view, 40 which will appear as the description proceeds, the invention consists in certain novel features of construction, arrangement and combination of parts hereinafter fully described, illustrated in the accompanying drawing, and particularly 45 pointed out in the appended claims, it being understood that various changes in the form, proportion, size and minor details of the structure may be made without departing from the spirit or sacrificing any of the advantages of 50 the invention.

For the purpose of facilitating an understanding of my invention, I have illustrated in the accompanying drawing, a preferred embodiment thereof, from an inspection of which, when considered in connection with the following description, my invention, its mode of construction, assembly and operation, and many of its advantages should be readily understood and appreciated.

Referring to the drawing in which the same 60 characters of reference are employed to indicate corresponding or similar parts throughout the several figures of the drawing:

Fig. 1 is a perspective view of a hair-waving pad or sachet involving my invention;

65 Fig. 2 is a perspective view of a developed sachet or envelope member;

Fig. 3 is a perspective view of a sachet or envelope in the process of manufacture;

Fig. 4 is a fragmentary view of a portion of 70 the perforated portion of the sachet;

Fig. 5 is a sectional view taken along the line 5-5 of Fig. 4.

Fig. 6 is a sectional view similar to that of Fig. 5, but having the burrs of the sachet pressed down.

The invention comprises a member designated generally by the reference character 10 formed into a sachet or envelope. Said member 10 consists of two layers, the inside layer 11 and the outside layer 12. The inside layer is of 5 metallic foil, which is adapted to react with a chemical or the like to produce exothermic reaction and evolve heat thereby. In the preferred form of my invention, the metallic member constituting the inside layer 11 of the member 10 is an extremely thin foil of chemically pure aluminum.

The outside layer 12 is a chemically inert member, such as glassine paper, and it is so intimately associated with the foil member 11 as to 15 form therewith in effect an integral sheet member 10.

Both members 11 and 12 are extremely thin, and the result is that the member 10 is handled as a sheet of paper or the like with no possibility of separation of the two constituent layers. The drawing, of course, shows the layers in highly exaggerated proportion to clarify the construction and to complete the disclosure thereof.

In this condition, a section 13 of the member 10, which is to form a face of the sachet, is perforated or pierced by a plurality of appropriate instruments to form by cutting, tearing or other operation, the slits or perforations 14. These perforations 14 are substantially "I-shaped" and 30 are formed from the inner face 11, so that the burrs or feather edges 15 are protruding from the outer face 12, which is the inert layer of the member 10.

The novelty of these perforations is in their 35 ability to permit moisture and still retain any powder or granulated mixture which may be disposed within the sachet or envelope formed by member 10. Perforations 14 may, to all intents and purposes, be closed, as by pressing down the 40 burrs 15 by rolling or the like. In this condition, the member 10 may be formed into an envelope or sachet, which will retain the powder or granulated chemicals or ingredients of the active mixture adapted to react with the metal 45 foil without danger of same sifting out, as aforesaid. At the same time, moisture will freely pass through the perforations when applied by means of a moistened member, not shown, to activate the chemical and cause the exothermic reaction. 50

After the member 10 has been provided with perforations, the portion along one of the edges is provided with paste, glue or other adhesive 16, and the member 10 is folded along the lines 17 and 18 and caused to form a substantially 55 flattened tube-like member, as shown in Fig. 3. In large-scale production, this substantially flattened tube-like member may be very long and may then be cut to proper lengths for the formation of individual sachets. It will be seen 60 that this substantially flattened tube-like member is somewhat elliptical in cross section with the minor axis of the ellipse very short as compared to the major axis thereof.

The substantially flattened hollow member 65 shown in Fig. 3 is then filled with the proper chemicals or mixture designated by the character 20, and the ends 19 of the hollow member are folded over to complete the envelope. The chemicals 20 70 are placed in the hollow member of Fig. 3 by folding one end, as at 19, up-ending the hollow member with the folded portion 19 at the bottom, filling the hollow member as required by pouring the materials 20 thereinto, and then fold- 75

ing the open end over as at 19 to complete the sachet.

The sachet is now ready for use and will remain in envelope form regardless of whether the 5 inner layer of foil is completely consumed by exothermic reaction or not. This is because the outer layer 12 is not affected by the reaction, giving rise to the advantages enumerated above. It is obvious also that the envelope or sachet 10 can be packed, shipped and handled without danger of the material 20 sifting out therefrom.

It is believed that my invention, its mode of construction and assembly, and many of its advantages should be readily understood from the 15 foregoing without further description, and it should also be manifest that while a preferred embodiment of the invention has been shown and described for illustrative purposes, the structural details are nevertheless capable of wide variation 20 within the purview of my invention as defined in the appended claims.

What I claim and desire to secure by Letters Patent of the United States is:

1. In a device of the character described, a 25 hair-waving pad of the exothermic chemical reaction type, including a sachet constructed from a bi-layered member and having a quantity of normally inactive material disposed therein, one of said layers adapted to be the external face of 30 said sachet and being of chemically inert material, the second of said layers adapted to be the

internal lining of said sachet and being of a material adapted to enter into chemical reaction with said material contained in said sachet when said last-mentioned material is moistened, and means for introducing moisture to said last-mentioned material, said last-mentioned means comprising perforations disposed upon the face of 5 said sachet, said perforations being slit-like and burred on the surface of said sachet, the burrs adapted to be substantially pressed down during handling thereof rendering the perforations 10 in effect self-closing.

2. A hair-waving pad of the character described comprising an envelope wholly constructed from prefabricated bi-layered sheeting, the 15 inwardly disposed layer being metal foil and being bonded to a layer of chemically inert material, and a quantity of chemicals contained within said envelope and exothermically reactive with said metal foil on moistening thereof, 20 and means for moistening said material, comprising perforations provided on a face of said envelope and extending through both of said layers, said perforations being formed from inside outward thereby causing burrs to be formed 25 on the outside thereof said burrs being adapted to be pressed down during the handling of said pad to prevent the chemicals within said envelope from sifting out and yet permit seepage of applied moisture thereinto. 30
